UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPE-WRITING MACHINE.

1,248,346.

Specification of Letters Patent. Patented Nov. 27, 1917.

Application filed June 20, 1916. Serial No. 104,678.

To all whom it may concern:

Be it known that I, ALFRED G. F. KUROWSKI, a subject of the German Empire, residing in Brooklyn borough, in the county of Kings, city and State of New York, have invented certain new and useful Improvements in Type-Writing Machines, of which the following is a specification.

This invention relates to typewriting machines in which a platen is mounted on a letter-feeding carriage, and certain features thereof relate particularly to machines in which the platen is shiftable up and down on the carriage in a direction transverse to the letter-feed travel, to different case positions.

An object of the invention is to provide suitable cushioning means between the platen and the carriage, to cushion the platen when the carriage is suddenly arrested, either in returning it for commencing a new line of writing, or when the carriage is permitted to run forward until arrested by a stop, as in tabulating operations. When the carriage and the platen are suddenly arrested, there is a tendency for the work-pieces on the platen to creep lengthwise thereof, owing to inertia, and although this creeping may be very slight at each individual stoppage of the carriage, the result is cumulative, and may throw the work out of adjustment to an objectionable degree in the course of typewriting a sheet.

The invention provides means whereby the platen, during the normal letter-feed movements of the carriage, is firmly held against endwise shake or movement relative to the carriage, while permitting the platen to yield slightly when the carriage is suddenly arrested, thereby avoiding said creeping of the work on the platen. Such means may comprise a stiff spring or buffer, which may also form a guide, mounted on the carriage to engage in a guideway on the platen frame, permitting the platen to shift to different case positions, while holding the platen against endwise movement relative to the carriage, except as such endwise movement is permitted by the resiliency of the guide. Said guide may yield slightly in the direction of the carriage travel or in the reverse direction, when placed under tension by the momentum of the platen as the carriage is suddenly arrested.

A further feature of the invention relates

to an improved adjustable stop device to arrest the platen when shifted to upper-case position, including means to permit refinement of adjustment and to securely hold the stop in adjusted position. The stop device 60 may comprise a stop-plate, mounted on the carriage and projecting into the path of the platen frame. The stop-plate may be secured to the carriage frame by a screw extending through an elongated slot in the 65 plate to permit adjustment of the stop. Said plate may be provided with an offset portion, to receive an adjusting screw threaded through said offset and having its end abutting the carriage frame. Said adjusting 70 screw, which may extend in the direction in which the platen shifts, permits a fine adjustment of the stop and serves to positively hold the stop-plate against displacement by the platen frame striking thereagainst. 75

Other features and advantages will hereinafter appear.

In the accompanying drawings,

Figure 1 is a side elevation of an Underwood typewriting machine with the present 80 invention applied thereto, many of the parts of the machine being omitted.

Fig. 2 is a fragmentary front perspective view of the machine.

Fig. 3 is a perspective view showing a resilient guide on the carriage and a slotted bushing on the platen frame in which said guide moves, the parts being separated to show the construction.

Fig. 4 is a part-sectional front elevation 90 showing a platen frame guide and stop and their relation to the platen when the latter is in lower-case position.

Fig. 5 is a similar view, with the platen frame and the platen in upper-case position. 95

The roller platen 10 is fixed to the platen axle 11, journaled in the ends of a platen frame 12, mounted on the carriage 13 and shiftable up and down thereon to upper and lower-case positions, to enable the upper and lower-case types 14 and 15 to print at the platen. The types are carried on type-bars 16, fulcrumed at 17, to swing upwardly and rearwardly to cause the types to strike against the front face of the platen. The 100 type-bars may be actuated by keys 18 on key levers 19, fulcrumed on a rod 20 and connected through bell-crank 21 to the type-bars. The carriage is mounted to travel on front and rear guide-rails 22 and 23 on the 110

machine frame 24, and may be driven in letter-feeding direction by the usual spring drum (not shown). The letter-feed movements of the carriage may be controlled by 5 the usual escapement mechanism, actuated by the type-bars through the usual mechanism (not shown). The machine may also be equipped with tabulating mechanism comprising a key or keys operable to release 10 the carriage from the control of the escapement mechanism, and allowing the carriage to run forward until arrested by a tabulator-stop.

The platen frame and platen are shiftable 15 to upper-case position by depressing shift-keys 25 on shift-key levers 26, fulcrumed on the rod 20 and having upstanding arms 27, to swing a shift frame 28 about its fulcrum 29, and thereby cause a shift-rail 30, forming 20 part of said shift frame, to lift the carriage. The connection between said rail 30 and the platen comprises a roll 31 on the platen frame, arranged to run on said shift-rail during the travel of the carriage. The 25 platen frame 12 is supported and guided in its case-shifting movements by rock arms 32, fixed to and extending forwardly from a rock shaft 33 on the carriage, the forward ends of the arms 32 being hooked to receive 30 gudgeons or studs 34 fixed to the platen frame.

The platen frame may comprise stops 35, which normally rest on the carriage frame 13, thereby determining the lower-case position 35 of the platen. The upper-case position of the platen is determined by stops 36, projecting inwardly toward the platen from stop-plates 37 adjustably mounted on the carriage. The platen frame ends are provided 40 with shoulders 36^a, which, when the platen frame is shifted upwardly, strike the stops 36, and thereby determine the upper-case position of the platen. The stop-plates 37 are mounted for vertical adjustment on 45 the front vertical faces of supporting blocks or frame-pieces 38, which form part of the carriage frame. The stop-plates are secured in adjusted position by clamping screws 39, which extend through slots 40 in the stop- 50 plates, said screws being threaded into the frame-pieces 38 to clamp the stop-plates thereto. The slots 40 are vertically elongated to permit adjustment of the stop-plates.

55 The lower ends 41 of the stop-plates are bent rearwardly to extend beneath the blocks 38, said ends being provided with screw-threaded openings to receive adjusting screws 42, the upper ends of which project 60 into sockets 43 in the carriage frame. The adjusting screws 42 assist in accurately adjusting the stop-plates 37 when the clamping screws 39 have first been loosened, after which the clamping screws 39 are set up to 65 securely hold the stop-plates in adjusted

position. The screws 42 further serve as set screws to receive the vertical thrust of the platen frame on the stops 36. That is to say, when the platen is shifted to upper-case position, so that the shoulders 36^a strike 70 the stops 36, the screws 42 hold the stop-plates solidly against any vertical movement, so that the clamping screws 39 need not be relied on to prevent the stops from working upwardly. As the strain on the 75 stops 36 is always in an upward direction, the screws 39 can be relied on to prevent downward displacement of the stops.

Endwise movement of the platen in the platen frame may be prevented by the hub 80 44 of the platen abutting against the platen frame end, and by the hub 45 of a hand-wheel 46 abutting against a bushing 47 secured to the platen frame and in which the platen axle 11 is journaled. Endwise movement or shake of the platen frame and platen in the carriage is prevented by a guide 48, mounted on the carriage and engaging in a guideway 49, formed by a rabbet or slot in the bushing 47. The vertical sides of the 90 guide 48 may fit between shoulders 50 and 51, formed respectively by the inner end of the slot 49 and the inner end of the hub 45, thereby preventing relative movement of the guide 48 and the platen, while permitting the platen frame and the platen to shift up and down freely relatively to said guide. 95

The guide-plate 48 is connected to the frame-piece 38 by means of arms 52 extending forwardly from the guide-plate on 100 opposite sides of the frame-piece 38 and secured to the latter by screws 53 extending through elongated slots 54 in said arms and threaded into the frame-piece. Said slots permit forward and rearward adjustment 105 of the guide-plate. The guide-plate 48 may be spaced a substantial distance from the rear face of the frame-piece 38, and is made of elastic or springy material to enable it to yield slightly in a direction lengthwise of the platen under the force applied thereto by the inertia or momentum of the platen, when a sudden blow is applied to the carriage. This occurs when the carriage is suddenly arrested, which may take place 110 either in returning the carriage to position for writing a new line, or when the carriage is permitted to run forward under the power of its driving spring until arrested by a stop, as in tabulating. The guide-plate 115 48 thus serves as a buffer or cushion between the carriage and the platen, preventing jarring or too sudden stoppage of the platen, which is particularly useful in preventing the work-sheets on the platen from 120 creeping or being moved lengthwise of the platen. The guide-plate 48, however, is of sufficient stiffness to serve as a practically rigid connection between the carriage and platen during the letter-feed movements 125 130 135 140

thereof. The guide-plate 48 may be made of spring steel or other suitable material and the arms 52 thereof may be bowed or bent, at 55, or otherwise shaped to permit 5 the stop to yield sufficiently for the purposes specified.

Variations may be resorted to within the scope of the invention, and portions of the improvements may be used without others.

10 Having thus described my invention, I claim:

1. In a typewriting machine, the combination with a carriage having a letter-feed travel, of a platen mounted on the carriage 15 to travel therewith, the platen being capable of a limited movement in either endwise direction relative to the carriage in letter-feeding direction, and a single cushioning means for normally holding the platen in 20 an intermediate position with respect to its movement relative to the carriage, said cushioning means serving to cushion the platen when a sudden blow is imparted to the carriage.
- 25 2. In a typewriting machine, the combination with a carriage having a letter-feed travel, of a platen mounted to shift thereon in a direction transverse to the letter-feed travel, to different case positions, and means 30 on said carriage for guiding the platen relatively thereto in its case-shifting movements, said guiding means yieldable in the direction of the carriage travel and serving as a cushion between the platen and carriage when the latter is subjected to a shock.
- 35 3. In a typewriting machine, the combi-

nation with a carriage, of a platen frame, a platen journaled therein, said platen and frame shiftable transversely to the direction of carriage travel, to different case positions, and a resilient guide by which the platen is guided in its case-shifting movements and normally held against movement relative to the carriage in letter-feeding direction, said guide forming a buffer, or 40 cushion, between the platen and carriage, permitting the platen to yield in the direction of the carriage travel.

4. In a front-strike typewriting machine, the combination with a carriage having a 45 letter-feed travel, of a platen frame, a platen having an axis journaled in said frame, a bushing secured to the platen frame and providing a bearing for the platen axle, said bushing having a guide- 50 way formed therein, a guide-plate mounted on the carriage in position to enter said guideway, and means for shifting the platen and platen frame up and down on the carriage to different case positions, said guide- 55 plate serving to normally guide the platen in its case-shifting movements and preventing endwise movement of the platen on the carriage, said guide-plate having a resilient connection with the carriage to form a 60 cushion permitting the platen to yield relatively to the carriage when the latter is suddenly arrested.
